UNITED STATES PATENT OFFICE.

JOHN B. MILLER, OF CHICAGO, ILLINOIS.

DESIGN FOR A HOT-WATER BAG.

SPECIFICATION forming part of Design No. 35,373, dated December 3, 1901.

Application filed July 22, 1901. Serial No. 69,336. Term of patent 7 years.

To all whom it may concern:

Be it known that I, JOHN B. MILLER, a citizen of the United States of America, residing at Chicago, in the county of Cook and State 5 of Illinois, have invented and produced a certain new and original Design for a Hot-Water Bag, of which the following is a specification.

The design is clearly shown in drawings accompanying this specification by means of 10 three figures, in which—

Figure 1 is a face view of the design looking in the direction of the arrow 1 in Fig. 2. Fig. 2 is an edge view, and Fig. 3 is a horizontal section in line 3 3 of Fig. 2.

15 The leading feature of my design resides in a water-bag having a rectangular outline, the front portion of which is approximately flat from side to side, but longitudinally concave from top to bottom, and the rear portion 20 of which is convex and merges into the front portion in rounded edges.

In front view the body of the design is approximately rectangular and in side view concavo-convex, while in plan or horizontal section the front face is flat from side to side, 25 while the rear face is bowed out or convex.

In the drawings, A' represents the front por-

tion of the design, which is approximately rectangular and flat across its face from a⁵ to a⁶, as seen in Fig. 3, while longitudinally of 30 the bag it is rounded in or concave, as seen in Fig. 2. The rear portion a⁸ is convex, the portion lettered a⁷ in Fig. 3 being the farthest from the front portion A', and from this point the portions A² A³ on opposite sides of the 35 point a⁷ extend toward the front portion A' in curved lines, which gradually merge into said front portion by rounded edges. From the upper end of the rectangular body projects a neck a', terminating in a flaring nozzle a². A loop a³ extends from the neck a', and a perforated lug a extends from the lower 40 end of the body.

The design presents a water-bag having a 45 novel and distinguished appearance.

I claim as new and desire to secure by Letters Patent—

The design for a hot-water bag, substantially as shown and described.

JOHN B. MILLER.
